DESIGN FOR A BOX

Evelyn G. Levkoff, Rockaway Park, N. Y.

Application January 5, 1934, Serial No. 50,324

Term of patent 14 years

To all whom it may concern:

Be it known that I, EVELYN G. LEVKOFF, a citizen of the United States, residing at Rockaway Park, in the county of Queens and State of New York, have invented a new, original, and ornamental Design for a Box, of which the following is a specification, reference being had to the accompanying drawing, forming part thereof.

I claim:—

The ornamental design for a box, as shown

EVELYN G. LEVKOFF.
